UNITED STATES PATENT OFFICE.

CLYDE G. LONGNECKER, OF CHICAGO, ILLINOIS.

BUMPER.

Application filed November 20, 1922. Serial No. 602,171.

To all whom it may concern:

Be it known that I, CLYDE G. LONGNECKER, a citizen of the United States, residing at Chicago, in the county of Cook and State of Illinois, have invented certain new and useful Improvements in Bumpers, of which the following is a description.

My invention relates to improvements in bumpers and more particularly to bumpers adapted to be positioned at the front or rear end, or both ends, of a motor vehicle in order to prevent injury to the same.

The invention has among its objects the production of a device described, which is simple, convenient, durable, reliable, neat and attractive in appearance, efficient and satisfactory for use wherever found applicable.

Another object of my invention is to provide a bumper of the kind described in which any thrust or blow given to any portion of the bumper will be absorbed or taken up throughout the entire bumper, thus reinforcing the bumper to a considerable extent and greatly improving its efficiency. A further object is the production of a device of the kind described which is adapted for all makes of automobiles, the brackets or supports being substantially universally adapted for the same, thereby reducing the expense of manufacturing and carrying in stock of many sizes and styles of brackets.

Many other objects and advantages of the construction herein shown and described will be obvious to those skilled in the art from the disclosures herein given.

To this end my invention consists in the novel construction, arrangement and combination of parts herein shown and described, and more particularly pointed out in the claims.

Fig. 1 is a front elevation of the bumper;

Fig. 2 is a top plan view thereof with a portion of the supporting brackets broken away;

Fig. 3 is a side elevation of the same as attached to a vehicle;

Fig. 4 is a section taken substantially on line 4—4 of Fig. 1, showing the vehicle in fragmentary elevation;

Fig. 5 is a section taken substantially on line 5—5 of Fig. 1;

Fig. 6 is a section taken substantially on line 6—6 of Fig. 2;

Fig. 7 is a section taken substantially on line 7—7 of Fig. 2; and

Fig. 8 shows a modified form of tie-bar.

In the drawings, wherein I have illustrated the preferred embodiments of my invention, there is shown a bumper adapted to be mounted upon either the front or rear ends of a motor vehicle, or both ends, if so desired, the vehicle being indicated at 1 and illustrated as having a frame 2 and wheels 3.

The bumper itself comprises an impact-receiving bar 4 of any desired size and material, preferably of a flexible resilient material such as steel, the ends of said bar provided with loops 5 formed in any desired or suitable manner. It will be noted that the loops are in the present instance formed integral with the remainder of the bar and the bar and its loops lie in a single plane.

A pair of flexed or bowed resilient bars or rods 6 and 7, respectively, are positioned across each of the loops 5, said bars 6 and 7 being arranged mutually transversely of each other and in the present instance the bars 6 are arranged transversely of the longitudinal direction of the bar 4, while the bars 7 are arranged in alignment therewith.

The bars 6 and 7 are arranged at the rear of the impact-receiving bar 4 and are preferably held in frictional contact therewith so that when the bar 4 receives an impact and is pressed inwardly the bars 6 and 7 may momentarily straighten out and slide along the bar 4. In order to provide for the securing of the flexed bars to the impact-receiving bar, the members 6 are provided with elongated slots 8 at their ends and through which are positioned screws or bolts 9, as shown more clearly in Fig. 5, said bolts being tightened up to such a degree that they will not prevent the relative sliding movement of the members 5 and 6 when said impact-receiving bar is pressed inwardly. The bars 7 are preferably fixedly secured to the bar 4 at one end as at 10, the other end 11 of the bar 7 being held in contact with the bar 4 by means of a clip 12, or the like. It will be particularly noted, especially in Figs. 4 and 5, that the flexed bars 6 and 7 are slidably engageable with one another, said bars being preferably made of a material having a rather high degree of flexibility and resiliency as for instance, spring, steel, or the like.

In order to mount the bumper upon the vehicle, I have provided brackets, said brackets in the present instance each comprising a pair of bars, one of which is secured to the frame of the vehicle, as at 13, and is slightly offset at its other end so as to engage with said frame, as at 14. The other of the pair of the bracket bars is bent to provide a pair of legs 15 and 16, the leg 15 having an elongated slot therethrough adapted to receive fastening bolts 16' for securing to the part 14 of the bar 13, whereby longitudinal adjustment is provided in order to space the bumper at the desired 10 distance in advance of the vehicle frame.

The bracket bar 6 is connected to the flexed member 7 intermediate the ends of said bracket bar, as shown more particularly in Fig. 4, so that a portion of said bracket bar extends beyond said point of securing, whereby it may be connected to a connecting rod or tie-bar, as will be hereinafter described.

The means for connecting the bracket bar 25 to the flexed bar 7 preferably comprises a clip 17 fixed to the bar 16 and only frictionally engageable with the bar 7, so that relative movement between the bar 7 and the bracket will be permitted when required.

Extending substantially parallel to the impact-receiving member 4 and preferably to the rear thereof is a tie-bar or connecting rod having its ends secured to the projecting ends 16 of the bracket bars. This tie-bar 18 is preferably made longitudinally adjustable by means of a turn-buckle 19 or any suitable or equivalent device, whereby the length of said tie-rod may be adjusted. Any blow or impact given to the bumper, 40 irrespective of whether said impact is perpendicular thereto, or at any other angle, will always be transmitted and distributed to both ends of the bumper and to the supporting brackets through said tie-rod so that said tie-rod serves as a very efficient 45 form of re-inforcement for the bumper. I prefer to employ lock nuts on the rods at the turn buckle so as to maintain the parts in the desired adjustment. The same may 50 also be employed at the ends adjacent the bar 16, if so desired.

Another essential function of the tie-rod is that it permits the bumper being applied to various makes of cars, having varying 55 widths of frames, for it is apparent that the tie-rod may be lengthened or shortened so that the brackets may be properly fastened to the frame of the vehicle.

In Fig. 8 I have shown a different form 60 of connecting rod, wherein the sockets 20 are adapted to be secured to the brackets 16 and a single rod 21 is reversely threaded at its ends and is engageable in said sockets. In order to more easily manipulate the bar 21 65 a portion thereof is made of a suitable non-

circular cross section as at 22, so that a wrench or other tool may be engaged thereat to rotate the bar 21. Lock nuts 20' are shown for maintaining the parts in the desired adjustment.

I have shown a slightly modified construction but embodying the essential features of the other types of bracket shown. Referring to this figure, 25-25 represent bracket parts similar to the parts 13, while 26 represents the bar, taking the place of the tie rod, and which is provided with the ends 27-27, taking the place of the bracket parts 15, while 28 corresponds with the clips 17 previously described. There is also shown an additional part 29, which may be secured to the part 26 to form an additional attachment of the same to a frame cross bar of the vehicle when the vehicle is so provided with one.

It will be particularly noted with the style of bracket shown that instead of having independent brackets arranged one at each side of the vehicle, there is provided substantially a single bracket, which is connected to each side of the vehicle frame. With the type illustrated in Fig. 2 the bracket is adjustable so that it may be placed on any car and adjusted as required, and reinforcing the front end of the automobile, thereby tending to stiffen the same and prevent bent frames. The same is also true when the device is applied at the rear.

The advantages of making what is substantially a single bracket attached to both sides of the car as well as one which is universal will be obvious to those skilled in the art. It should also be noted that with the bracket construction similar to that shown and described, practically any of the types of impact bars now in the market may be secured to my improved bracket in lieu of the impact bars that I have shown. The factory may therefore provide the brackets as standard equipment desired and let the purchaser apply his own type of impact bar.

Having thus described my invention, it is obvious that various immaterial modifications may be made in the same without departing from the spirit of my invention; hence I do not wish to be understood as limiting myself to the exact form, construction, arrangement and combination of parts herein shown and described or uses mentioned.

What I claim as new and desire to secure by Letters Patent is:

1. In combination, a bumper, brackets at the ends thereof for mounting said bumper on a vehicle, said brackets comprising members each connected at one end to said vehicle and thence bent laterally between its ends toward the other, means for connecting said bent portions of said members to said bumper intermediate their ends so that said

bent portions project beyond the points of securing, and a tie rod connected at its ends to said projecting portions of the brackets.

2. In combination, a bumper and brackets at the ends thereof for mounting said bumper on a vehicle, said brackets each comprising a pair of adjustably connected bars, one of said bars connected at one end to said vehicle and the other of said bars laterally bent between its ends, means for connecting said bent bars to said bumper intermediate their ends so as to have a portion of the bent bar projecting beyond said point of securing, and a tie-rod connected at its ends to said projecting portions of the brackets.

3. In combination, a bumper and brackets at the ends thereof for mounting said bumper on a vehicle, said brackets each comprising a pair of adjustably connected bars, one of said bars connected at one end to said vehicle and the other of said bars laterally bent between its ends, means for frictionally connecting said bent bar to said bumper intermediate its ends so as to have a portion of the bent bar projecting beyond said point of securing, and a tie-rod connected at its ends to said projecting portions of the brackets.

4. A bumper comprising a bar provided with loops at its ends, a flexed member connected across each of said loops transversely of said bar, a member across each of said loops longitudinally thereof and slidably engageable with one of said flexed members, and brackets adapted to be connected at one of their ends to a vehicle and at their other ends to said members.

5. A bumper comprising a bar provided with loops at its ends, a flexed member connected across each of said loops transversely of said bar at the rear thereof, a flexed member across each of said loops longitudinally thereof and slidably engageable with one of said first mentioned flexed members, and brackets adapted to be connected at one of their ends to a vehicle and at their other ends to said flexed members.

6. A bumper comprising a bar provided with loops at its ends, all lying in the same plane, a pair of mutually transverse flexed members connected to said bar across each of said loops and slidably engageable with each other, and brackets for connecting said flexed members to a vehicle.

7. A bumper comprising a bar provided with loops at its ends, all lying in the same plane, a pair of mutually transverse flexed members frictionally connected to said bar

across each of said loops and slidably engageable with each other, and brackets for connecting said flexed members to a vehicle.

8. A bumper comprising a bar provided with loops at its ends and lying in the same plane, a flexed bar frictionally connected at its ends transversely across each of said loops, a flexed member connected across each of said loops in a direction transverse of said first-mentioned flexed bar and slidably engageable therewith, means for frictionally securing one end of said last-mentioned flexed members to said bar so as to permit sliding movement therebetween, and brackets adapted to be secured at one end to said flexed members and at their other end to a vehicle.

9. A bumper comprising a bar of a single piece of metal provided with loops at its ends and lying in the same plane, a pair of mutually transverse flexed members across each of said loops and in slidable engagement with each other, said flexed members frictionally connected to said bar so as to permit relative sliding movement therebetween, and brackets connected between said flexed members for securing to a vehicle.

10. A bumper comprising a bar of a single piece of metal provided with loops at its ends and lying in the same plane, a pair of mutually transverse and slidably engageable flexed members across each of said loops, said flexed members frictionally connected to said bar so as to permit relative sliding movement therebetween, brackets connected between said flexed members for securing to a vehicle, and a tie-rod substantially parallel to said first mentioned bar and connected between said brackets.

11. A bumper comprising a bar provided with loops at its ends and lying in the same plane, a pair of flexed members arranged mutually transverse across each of said loops and in slidable engagement with each other, means for frictionally connecting said flexed members to said bar so as to permit relative sliding movement therebetween, adjustable brackets connected between said flexed members for securing to a vehicle, and a longitudinally adjustable tie-rod connected at its ends to said brackets.

In testimony whereof, I have hereunto signed my name in the presence of two subscribing witnesses.

CLYDE G. LONGNECKER.
